GILBERT G. DAVIS AND MATTHEW J. DAVIS, OF VANCOUVER, BRITISH COLUMBIA,
CANADA.

LOG RAFT.

Application filed May 17, 1923, Serial No. 639,664. Renewed April 22, 1924.

To all whom it may concern:

Be it known that we, GILBERT G. DAVIS and MATTHEW J. DAVIS, both residents of the city of Vancouver, in the Province of 5 British Columbia, Canada, have invented certain new and useful Improvements in Log Rafts, of which the following is a specification.

Our invention relates to improvements in 10 log rafts the objects of which are to provide first a means of construction by which a raft can be built up of a plurality of tiers of logs, the floor of the raft being flat to permit of having great loading capacity 15 with a minimum draught to facilitate the removal of the raft from shallow waters, another object is to provide for a minimum towing effort being required by arranging the several logs subject to immersion longitudinally of the raft, and a further object 20 is to provide a means whereby the raft is securely bound together that it may be towed through rough seas without loss of logs. Our invention consists essentially of 25 a raft floor of logs bound together upon which further tiers of logs are loaded and bound, as will be more particularly described in the following specification, in which:—

30 Fig. 1 is a transverse section of our invention.

Fig. 2 is a sectional plan view taken on the line 2—2 of Fig. 3.

Fig. 3 is a longitudinal section and part 35 elevation taken on the line 3—3, of Fig. 2.

In the drawings like characters of reference indicate corresponding parts in each figure.

The numeral 1 indicates a plurality of 40 logs laid longitudinally of the raft to form a floor 2, the logs 1 being bound transversely together by ropes 3 which are fastened at their outer ends around a pair of side sticks 4 as at 5. The numeral 6 indicates 45 a tier of logs of length equal to the width of the floor 2, the logs at opposite ends of the tier 6 being suitably bound down to the outer logs 1 of the floor 2 by cables 7. The numeral 8 indicates a further tier of logs 50 laid transversely of the floor, which are of similar length to those in tier 6. 9 indicates longitudinally disposed side logs running from end to end of the raft upon the outer ends of the logs forming tier 8, and 10 is

a tier of logs laid transversely of the raft 55 between the side logs 9.

The numeral 11 indicates a plurality of cables passing around one side stick 4 over the tier 10 and the side logs 9 and around the opposite side stick 4, the opposite ends 60 of the cable being bound upon itself as at 12.

The numerals 13, 14 and 15 indicate further tiers of logs laid up upon the raft in the manner before described, 16 being 65 further side logs disposed longitudinally on both sides of the raft abutting the ends of the logs forming the tier 15, the end logs of the tier 13 being bound to the side logs 9 by cables 17.

When sufficient transverse tiers have been laid, a tier 18 is superimposed with logs laid longitudinally to approximately cover the raft. 19 indicates a plurality of cables passing around one of the side sticks 4 over 70 the top tier 18 and around the other side stick 4, the cables being fastened back upon themselves as indicated at 20. The numeral 21 indicates a plurality of cables which are first passed around any one of the logs forming the raft floor 2 and fastened upon themselves each of which cables are brought up between successive tiers (as is more particularly shown in Fig. 3) and are brought

75 out to the end of the raft over any desired 80 tier and are fastened securely to the outer end of the floor log from which they each started, thus preventing the ends of the raft from becoming dislodged during the towing 85 of the raft in rough seas. The numeral 22 90 indicates a pair of cables attached adjacent one end of the side sticks 4 and connected at their opposite ends to the tow line (not 95 shown) of the tug.

From the foregoing it will be seen that 100 we have invented a raft which may be constructed for towing in shallow waters and which is bound in a manner to withstand rough seas without damage, and which can be readily and safely dismantled at destination.

What we claim as our invention is:

1. In a log raft, a raft floor comprising 105 longitudinally disposed logs and binding means connecting such logs transversely together, a plurality of tiers of transversely disposed logs carried upon the floor, side logs carried upon certain of the spaced

2 apart tiers, transversely disposed logs between said side logs and means for binding said side logs to the tier of transversely disposed logs next above the side logs, and 5 means for binding the several tiers to the raft floor.

2. In a log raft, a raft floor comprising longitudinally disposed logs and binding means connecting the logs together, a plurality of tiers transversely disposed upon the floor, side logs at the ends of certain of the spaced apart tiers and means for binding the endmost transverse logs of a tier to the side logs of tier next below.

15 3. In a log raft, a raft floor comprising longitudinally disposed logs and binding means connecting such logs transversely together, a plurality of tiers of transversely disposed logs carried upon the floor, means 20 for binding the endmost logs of successive tiers of transverse logs to the raft floor adjacent its opposite ends.

4. In a log raft, a raft floor comprising

longitudinally disposed logs and binding means for connecting such logs transversely together, a plurality of tiers of transversely disposed logs carried upon the floor, a tier of longitudinally disposed logs upon the topmost transverse tier, side sticks bound at each side of the raft and to the raft floor, 25 and means connected to one side stick and passing over the topmost tier and secured to the other side stick to bind the several tiers together.

Dated at Portland, Oregon, this 24th day 35 of April, 1923.
